UNITED STATES PATENT OFFICE.

DENNIE M. DORMAN, OF GENEVA, NEW YORK.

VALVE-SPRING HOLDER.

Application filed December 17, 1926. Serial No. 155,453.

This invention relates to an improved automotive accessory and has more particular reference to an improved valve spring holder.

5 I am aware, of course, that a multitude of different kinds of devices known as valve lifters and valve spring lifters have been patented and marketed for use in connection with internal combustion engine valves for 10 maintaining the coiled springs in compressed condition to permit removal of the spring cup retainer, and subsequent removal of the valve and stem for grinding of the valve seat. Most of these devices, however, comprise intricate tool structures made up of 15 levers and links frequently so constructed as to render the same undependable and difficult to manipulate.

Briefly, the present invention relates to a 20 one-piece body in the form of an open ended cylinder adapted to surround the lower end of the valve stem and the upper end of the valve push pin, the same being engaged at its upper end with the spring cup and at 25 its lower end with the push pin guide. I am also aware that devices of this general character such as shown in Patent No. 1,113,258 to O. E. Stewart, October 13, 1924, and No. 1,185,241 to R. D. Radcliff, May 30, 1916, are old.

It follows that my primary aim is to improve upon valve spring lifters of these general types by providing one wherein the cylinder is formed on one side with finger notches to facilitate gripping and removal 35 of the horse shoe or cotter pin such as is used on the valve stem for holding the cup in place.

Another feature is in having the lower end 40 of the cylinder constructed in a manner to fit snugly down and over the push pin guide to prevent accidental displacement of the device and consequent displacement of the valve spring.

45 Other features and advantages of the invention will become apparent from the following description and drawing.

In the accompanying drawings forming a 50 part of this application and in which like numerals are employed to designate like parts throughout the same:

55 Figure 1 is a fragmentary sectional and elevational view of a portion of an internal combustion engine valve structure showing the improved valve spring holder associated therewith.

Figure 2 is an enlarged side view of the same showing the construction as it operates more plainly.

Figure 3 is a view somewhat like Figure 2 60 showing a more modern type of push pin guide, and the manner in which the invention cooperates therewith.

Figure 4 is a perspective view of the invention per se. 65

In the drawing, the reference character 1 designates a valve of the mushroom type provided with a central stem 2 extending down through a guide 3 in the cylinder block, which is also provided with a valve 70 seat 4. The crank case is represented at 5, and rotatable in this is a cam shaft 6 having a cam 7 engaging the lower end of the push pin or tappet rod 8. This extends up through a bored protuberance 9 functioning 75 as a guide. The usual valve spring 10 surrounds the stem and rests in an ordinary cup 11 held in place by a horse shoe retainer 12. Of course, all of these parts are of conventional form and constitute no part of the 80 invention, being shown merely for the purpose of demonstration of the operation of the invention.

The invention is generally represented by the reference character 13 and as before 85 stated it is in the form of a single body of general cylindrical form represented at 14. This is open at its opposite ends, and one side is cut away and the edges thereof are formed with curved finger notches 15 which, 90 obviously, serve to permit removal of the horse shoe retainer 12 as represented in Figure 2. I have designated a portion 16 as a web and wish to call attention to the fact that this serves to surround the guide 9 as 95 shown in Figure 2 and to be jammed tightly over the same in telescoping relation to prevent displacement of the device.

In operation, the cam shaft 6 is so turned as to elevate the valve 1 off of the seat 4 as 100 represented in Figure 1, thus compressing the spring 10. This spaces the valve stem from the push rod in an obvious manner, thus affording sufficient space to permit the relatively thin gage metal cylinder to be 105 passed therebetween and then set in an upright position between the guide 9 and the under side of the valve spring cup 11. Now the valve may be lowered so as to bring the horse shoe down opposite the finger notches 110 to permit it to be removed and to permit subsequent removal of the valve and its stem.

Even after the valve is removed the spring is maintained in compressed condition so as to permit efficient resurfacing of the valve seat.

5 It is to be stated that the only difference between Figure 3 and the other figure is that a more modern type of tappet pin guide is shown, the same being in the form of a removable bushing. In this instance the 10 vice bears down on the top flange of the bushing.

It is believed that by considering the description in connection with the drawing a clear understanding of the invention will be 15 had. Therefore, a more lengthy description is thought unnecessary.

While the preferred embodiment of the invention has been shown and described, it is

to be understood that minor changes in shape and size, may be resorted to without departing from the spirit of the invention as claimed.

Having thus described the invention, what I claim is:—

As a new product of manufacture, a valve 25 spring lifter of the class described comprising an open ended cylinder having the major part of one side cut away to provide an entrance, the opposite edges of the entrance being formed with finger notches, and the 30 lower portion of said cylinder being in complete cylindrical form to permit it to be telescopedically engaged with a valve push pin guide.

In testimony whereof I affix my signature.

DENNIE M. DORMAN.
